UNITED STATES PATENT OFFICE

168,788

TABLE TENNIS BAT

George H. Forsyth, Chicago, Ill.

Application February 28, 1952, Serial No. 18,697

Term of patent 14 years

(Cl. D34—5)

To all whom it may concern:

Be it known that I, George H. Forsyth, a citizen of the United States, residing at Chicago, in the county of Cook, State of Illinois, have invented a new, original and ornamental Design for Table Tennis Bat, of which the following is a specification, reference being made to the accompanying drawings, forming part thereof, where-in:

Figure 3 is an enlarged side view of the handle end of the table tennis bat with the bat partially omitted for convenience in illustration;

The essential features of my design are shown in full lines.

I claim:

The ornamental design for a table tennis bat, as shown and described.

GEORGE H. FORSYTH.
